UNITED STATES PATENT OFFICE.

HERBERT EMBREE, OF HAMILTON, ONTARIO, CANADA.

MANTLE SEWING-MACHINE.

1,376,324.

Specification of Letters Patent. Patented Apr. 26, 1921.

Original application filed September 10, 1917, Serial No. 190,649. Divided and this application filed March 9, 1920. Serial No. 364,502.

To all whom it may concern:

Be it known that I, HERBERT EMBREE, residing at the city of Hamilton, in the county of Wentworth, in the Province of Ontario, Canada, have invented certain new and useful Improvements in Mantle Sewing-Machines, of which the following is the specification.

My invention relates to improvements in mantle sewing machines, this application being a divisional application arising out of parent application Serial No. 190,649, filed Sept. 10, 1917, on which Patent No. 1,342,669 was granted on June 8th, 1920, and the object generally is to provide means for quickly, efficiently and automatically threading the needles of the mantle sewing machine with cord portions automatically cut from the stock as hereinafter more particularly explained by the following specification.

Figure 1, is a section plan view of the needle threading mechanism of my mantle sewing machine and parts co-acting therewith taken on line 1—1 Fig. 2.

Fig. 2 is a longitudinal section through the parts shown in Fig. 1.

Fig. 3 is an end elevation of my machine looking in the direction of arrow Fig. 2.

Fig. 4 is a sectional view on line 4—4, Fig. 2.

Fig. 5 is a sectional view on line 5—5, Fig. 2.

Fig. 6 is a sectional view on line 6—6, Fig. 2.

Fig. 7 is a sectional view on line 7—7, Fig. 2.

Fig. 8 is an enlarged sectional detail on line 8—8 Fig. 1 showing the parts in the position they assume when the thread is being drawn through the eye of a needle.

Fig. 9 is a view similar to Fig. 8 showing the parts in the position they assume prior to gripping the thread and passing it through the eye of a needle.

Fig. 10 is a sectional detail on line 10—10, Fig. 5.

Fig. 11 is a sectional view through the thread gripping arm showing the parts in the position they assume when ready to grip the thread.

Fig. 12 is a view similar to Fig. 11 showing the parts in the position they assume when gripping the thread.

Fig. 13 is a view similar to Figs. 11 and

12 showing the parts in the position they assume after having released the thread.

Fig. 14 is an enlarged perspective detail of the thread looping device.

Fig. 15 is an enlarged perspective detail of the thread carrier.

Fig. 16 is an enlarged perspective detail of the main operating cam.

Fig. 17 is a detail of the plate used for securing the needle ends in position.

Fig. 18 is an enlarged detail of the block 184.

Fig. 19 is a detail of the cam plate 250.

Fig. 20 is a sectional view on line 20—20, Fig. 5.

In the drawings like letters of reference indicate corresponding parts in the various figures.

1 indicates the base of my machine. 2, 3 and 4 indicate standards secured by the base 1 and extending upwardly therefrom.

5 indicates a standard plate extending upwardly from the base 1 in proximity to the opposite end thereof to the standard 2.

6 indicates the main shaft which is journaled in the standards 2, 3 and 4 and standard plate 5. 7 indicates the operating lever secured to the outer end of the shaft 6 against the standard 2. 8 indicates a cam sleeve secured to the shaft 6 and provided with a cam groove 9, the main body of

which is spiral and provided at one end with an offset portion 9^x. 1^x indicate lugs extending upwardly from the base plate 1 beneath the cam sleeve 8. 10 indicates a lever provided at its lower end with a semi-circularly forked portion 11, the arms 11^x of which are swung upon the cross pin 12 secured in the lugs 1^x.

The upper end of the lever is provided with a forked portion 13 provided with longitudinal slots 13^x for a purpose which will hereinafter appear.

2^x indicates a lateral lug extension to the standard 2 and 3^x indicates a lateral lug extension to the standard 3. 14 indicates a rod secured at one end in proximity to the upper end of the standard 2 and at the opposite end in proximity to the upper end of the standard 3. 15 indicates a supplemental rod extending parallel to the rod 14 and secured at one end in the lug extension 2^x and at the opposite end in the lug extension 3^x. 16 indicates a block slidably held upon the rod 14 and provided with a lateral extension 16^x slidably held upon the 110

lever provided at its lower end with a semi-circularly forked portion 11, the arms 11^x of which are swung upon the cross pin 12 secured in the lugs 1^x.

The upper end of the lever is provided with a forked portion 13 provided with longitudinal slots 13^x for a purpose which will hereinafter appear.

2^x indicates a lateral lug extension to the standard 2 and 3^x indicates a lateral lug extension to the standard 3. 14 indicates a rod secured at one end in proximity to the upper end of the standard 2 and at the opposite end in proximity to the upper end of the standard 3. 15 indicates a supplemental rod extending parallel to the rod 14 and secured at one end in the lug extension 2^x and at the opposite end in the lug extension 3^x. 16 indicates a block slidably held upon the rod 14 and provided with a lateral extension 16^x slidably held upon the 110

lever provided at its lower end with a semi-circularly forked portion 11, the arms 11^x of which are swung upon the cross pin 12 secured in the lugs 1^x.

The upper end of the lever is provided with a forked portion 13 provided with longitudinal slots 13^x for a purpose which will hereinafter appear.

2^x indicates a lateral lug extension to the standard 2 and 3^x indicates a lateral lug extension to the standard 3. 14 indicates a rod secured at one end in proximity to the upper end of the standard 2 and at the opposite end in proximity to the upper end of the standard 3. 15 indicates a supplemental rod extending parallel to the rod 14 and secured at one end in the lug extension 2^x and at the opposite end in the lug extension 3^x. 16 indicates a block slidably held upon the rod 14 and provided with a lateral extension 16^x slidably held upon the 110

lever provided at its lower end with a semi-circularly forked portion 11, the arms 11^x of which are swung upon the cross pin 12 secured in the lugs 1^x.

The upper end of the lever is provided with a forked portion 13 provided with longitudinal slots 13^x for a purpose which will hereinafter appear.

2^x indicates a lateral lug extension to the standard 2 and 3^x indicates a lateral lug extension to the standard 3. 14 indicates a rod secured at one end in proximity to the upper end of the standard 2 and at the opposite end in proximity to the upper end of the standard 3. 15 indicates a supplemental rod extending parallel to the rod 14 and secured at one end in the lug extension 2^x and at the opposite end in the lug extension 3^x. 16 indicates a block slidably held upon the rod 14 and provided with a lateral extension 16^x slidably held upon the 110

lever provided at its lower end with a semi-circularly forked portion 11, the arms 11^x of which are swung upon the cross pin 12 secured in the lugs 1^x.

rod 15. The front portion of the upper face of the block 16 is provided with a recessed portion 17 in which fits a steel plate 18 having oppositely set L-shaped grooves 19 and 20. 21 and 22 indicate needles provided with out-turned ends 24, which fit into the L-shaped grooves 19 and 20. 25 indicates a plate superimposed upon the plate 18, the plates 25 and 18 being secured together and to the block 16 by a screw 26 passing therethrough. 27 and 28 indicate rollers carried by the block 16, one of such rollers being journaled on a suitable pin 27^x and the roller 28 being journaled on a reduced portion of the block extension 16^x. The rollers 27 and 28 extend into the slots 13^x to co-act with the forked lever 10. The needles 21 and 22 are provided with the usual eyes 30. 34 is a perforated guiding plate by which the needles are guided.

35 indicates a roller journaled on a pin 36. The roller 35 extends into the spiral groove 9 to co-act therewith. By turning the lever 7 in the direction of arrow (see Fig. 1) the cam sleeve 8 is rotated, the groove 9 thereof engaging the roller 35 and thereby swinging the lever 10 on its pivot formed by the cross pin 12. By this means the upper end of the lever 10 is swung inwardly carrying with it the block 16 which is connected thereto by means of the rollers 27 and 28 engaging the slots 13^x. By this means the needles 21 and 22 are carried forward to perform their operation.

35 156 indicates a cam secured to the shaft 6 such cam being provided with a cam recess 158 and provided with an inclined portion 159 and at the opposite end with a steep portion forming a shoulder 160.

40 175 indicates a rocking shaft journaled in the standards 3 and 4. One end of the rocking shaft 175 extends beyond the standard 3. 176 indicates a gravity dog secured to the end of the rocking shaft 175, the end of the dog normally resting upon the periphery of the cam 156. It will be noted that the end of the gravity dog 176 is curved at 177 for a purpose which will hereinafter appear. 178 indicates an arm which is secured to the opposite end of the rocking shaft 175. 179 indicates a tension spring connecting the free end of the arm 178 to a suitably located pin 180. 181 indicates a vertically extending recess formed in the center of the standard 4 and extending from the top thereof. 182 indicates a block slidably held in the recess 181 and provided with flange extensions 183 bearing against the outer face of the standard 4. 184 indicates a block

60 secured in a stationary position within the upper end of the recess 181 by means of the laterally extending flanges 185, which are secured to the top of the standard by screws 186. The block 184 is provided with a forward extension 184^x. 187 and 188 indicate

grooves formed in the upper face of the block and extending parallel with the longitudinal axis of the machine. The grooves 187 and 188 are in a line with the needles 21 and 22, the eyes of the needles passing thereto at 70 the end of the forward movement of the needles.

189 indicates a groove formed in the block extension 184^x and extending at right angles to the grooves 187 and 188. 190 and 191 indicate slots formed in the block 184 and extending through the base of the grooves 187. 192 indicates a rod fitting at its upper end into a recess 193 formed in the center of the lower face of the block 184. The lower end 80 of the rod 192 bears against the lower end of the recess 181 and passes freely through the block 182. The numerals 194 indicate recesses formed in the block 182 at each side of the rod 192. 195 and 196 indicate ribbon 85 fingers secured at their lower ends in the recesses 194, the fingers 195 and 196 being secured in each recess and extending upwardly into each slot 190 and 191 in the position shown in Fig. 8. 197 indicate spring fingers 90 carried by the rod 192 so as to extend upwardly in each slot 190 and 191 to press outwardly against the ribbon fingers 195 and 196. The upper ends of the ribbon fingers 195 and 196 are in such a position that when 95 the eyes of the needles pass into the grooves 187 and 188 an eye of a needle is directly above each slot 190 and 191 and, therefore, directly over the upper ends of the ribbon fingers 195 and 196, which are operated as 100 hereinafter described to pass upwardly through the eye of a needle. 198 indicates a post which extends upwardly from the block 184 for engaging the looped portion of the cord as the needles recede.

105 It will be noted on referring to Fig. 9 that the upper ends of the ribbon fingers 195 and 196 spread outwardly when free from compression of the spring 197 so as to form a receiving notch for the cord, which they are 110 designed to draw through the eye of a needle.

198^x indicates a link pivotally connected at one end to the arm 178 and at the opposite end to the block 182.

115 I will now describe the mechanism by which the cord is fed and cut into short portions and the ends of such portions carried so as to be gripped by the ribbon fingers 195 and 196 hereinbefore described. The standard plate 5 hereinbefore referred to is provided with an arc-shaped upper edge having a peripheral groove 5^x. 201 indicates a bracket which is secured by screws 202 to the face of the standard plate 5 so 120 as to extend over the edge thereof. 203 indicates a head formed integral with the bracket 201, such head being provided with a bore 204. 205 indicates a piece of hardened steel which is forced into the bore and 125 130

provided with a perforation 206 having a flared outer end 207. 208 indicates the cord, the body of which is wound upon a suitable reel and the end threaded into the perforation 206 as indicated in Fig. 5. The head 204 is provided with a lateral extension 209. 210 indicates a cutting knife which is arc-shape in form and provided with a cutting edge 211. 212 indicates a pin by which one end of the knife is pivotally connected to the lug extension 209. 213 indicates a rib. It may be stated that the upper edge of the standard 5, the upper edge of the bracket 201 and the upper edge of the rib 213 are all concentric with the center of the shaft 6. 214 indicates a concentric slot formed in the rib 213. 215 indicates a slide piece provided with an arc-shape groove 216 designed to fit the arc-shape rib 213. 217 indicates pins extending through the slide piece 215 and through the arc-shape slot 214. The lower end of the slide piece 215 is provided with opposing lugs 218. 219 indicates a sleeve interposed between the lugs 218. 220 indicates a set screw extending through such sleeve piece and through the lugs 218. 221 indicates a spring finger secured at one end to the sleeve 219 and provided at its opposite end with a forwardly presented ratchet rack 221* designed to be held in engagement with the cord 208. 222 indicates an arm provided with a collar-like end 223 swung upon the main shaft 6.

On referring to Fig. 2 it will be seen that the corresponding end of the main shaft is provided with a reduced threaded portion 6*. 224 indicates a cam secured on such reduced portion, such cam being provided with a cam way 225, the portion 226 of which is concentric and the portion 227 extending inwardly in an arc-shape direction toward the center of the cam. 229 indicates a depending lug extending from the arm 222. 230 indicates a link pivoted at one end by the screw 231 to the lug 229, and extending at its opposite end to the inner face of the cam 224. 232 indicates a roller mounted upon a pin 233 extending from the link 230, such roller co-acting with the cam way 225. 234 indicates a pitman connected at one end to the pin 233 and at the opposite end to the free end of the cutting knife 210. It will thus be seen that when the pitman is drawn by the roller into the eccentric portion of the cam way 225 that the knife 210 is drawn inwardly to sever the cord extending through the perforation 206.

It will be noted on referring to Figs. 1 and 3 that the upper end of the arm 222 is curved inwardly at 235 and is provided with a lug-like extension 236. 237 indicates a pin extending through such extension into the bracket 201. 238 indicates a sleeve mounted upon such pin and provided at its inner end 65 with an inwardly extending arm 238* and at

its opposite end with an outwardly extending arm 239. 240 indicates a roller carried by the inner end of the inwardly extending arm 238* and 241 indicates a leaf spring carried by the arm 222 and bearing upwardly 70 against the roller 240. 242 indicates a screw extending through the outer end of the outwardly extending arm 239 into the slide piece 215. 243 indicates an arm swung upon the main shaft 6. 244 indicates a disk secured to the main shaft 6, such disk being provided with a circumferentially extending slot 245 and a notch 246, one side 247 of the notch being inclined and the other side 248 substantially at right angles to the bottom 80 of the notch. 249 indicates a stud adjustably secured in the slot 245. 250 indicates a cam plate. The cam plate 250 comprises a central portion 251 having a central opening 252 through which the shaft 6 freely extends. 253 indicates a portion depending from the central portion 251 and terminating in an enlarged portion 254 provided with a concentric slot 255. 256 indicates a screw having an enlarged head, the shank 90 of the screw extending into the base plate 1 and the head bearing against the outer face of the enlargement 254 thereby securing such enlargement in a stationary position against the end of the base plate. 257 95 indicates a cam piece extending upwardly from the central portion 251, the upper edge of such cam piece being concentric with the center of the shaft 6 and flush with the outer periphery of the disk 244, the upper corner 100 of such cam piece 257 being preferably chamfered off at 258. 259 indicates a gravity dog carried by the arm 243, the depending portion 259* of which is provided with a lateral extension 260, which extension is designed to be brought into engagement with the upper peripheral edge of the cam piece 257 so as to carry the depending portion 259* out of the notch 246. The arm 243 is provided with a hollow portion 261, such 110 hollow portion being provided with longitudinally aligned slots 262 and 263. The upper end of the arm 243 is provided with a jaw portion 264. 265 and 266 indicate gripping jaw members. The member 266 is 115 mounted on a cross pin 267 passing through the jaw 264. 268 indicates a tail piece formed integral with the jaw member 266, such tail piece being provided with a slot 269 provided with an enlargement at its 120 lower inner end forming a shoulder 270. 271 indicates a bracket carried by the arm 243. 272 indicates a finger pivotally connected at 273, the end of such finger extending below the pivot point being provided 125 with a spring finger extension 274 designed to bear against the arm 243. The upper end of the finger 272 fits into the slotted enlargement forming the shoulder 270. 275 indicates a tension spring connected at one end 130

to the extreme end of the tail piece 268 and at the opposite end to the bracket 271. 276 indicates a cam plate comprising a bar portion 277 formed concentric with the center 5 of the shaft 6 and having at one end a radial enlargement 278 having an inclined inner edge portion 279 and a lateral extension 280 provided with an inclined portion 281. 282 indicates a bracket provided with a sleeve-like portion 283 extending at right angles to the edge of the plate 5 and to the outer end of which the cam plate 276 is secured by means of a screw 284 extending through the portion 283 and cam plate 276. The 10 bracket 282 is adjustably secured to the plate 5 by means of a set screw 285 extending through the bracket 282 and an arc-shaped slot 286.

It will be understood that as the arm 243 20 swings into the position shown in Figs. 3 and 4 that the cam plate 276 passes between the arm and the finger 272 carrying the finger 272 into engagement with the inclined portion 281 forcing such finger outwardly 25 against the pressure of the spring 274 so as to carry the opposite end of the finger clear of the shoulder 270 allowing the jaw member 266 to be drawn downwardly by means of the tension spring 275, the finger 272 passing 30 through the slot 269. As the arm 243 swings in the opposite direction or toward a vertical position the tail piece of the jaw member 266 engages with the inclined portion 279 of the cam plate enlargement 278 35 thereby carrying the tail piece upward and restoring the jaw member 266 to its normal position, the finger 272 being simultaneously carried again into engagement with the shoulder 270 by means of the spring 274.

40 287 indicates a pin extending inwardly from the arm 243, such pin being located at the lower end of the slot 202. The jaw member 265 is provided with a shank 288, which fits into the hollow portion of the arm 243. 289 indicates a pin extending outwardly from the shank 288 through the slot 263 and, therefore, in longitudinal alignment with the pin 287. 290 indicates a compression spring extending between the bottom of the hollow member 243 and the lower end of the shank 288. 291 indicates a stud extending outwardly from the bracket 201, the outer end of the stud being formed into a jaw through which extends a pin 292. 293 55 indicates an arm swung upon a pin 292. 294 indicates a tension spring connected at one end to the lower end of the arm 293, and at the opposite end by suitable means to the bracket 201. The upper end of the arm 293 60 is provided with an enlargement or head 295, which is spear-shape in form, the tip of the spear being slightly bent inwardly at 296. It will be noticed that the arm 293 forming the shank of the spear is located 65 at one side of the head and immediately

below the center portion of the head is formed a channel portion 297. As the arm 243 is swung over to the opposite angular position to that shown in the drawing the inturned tip of the spear head engages the 70 inner face of the arm 243 and is slightly forced inwardly and passes between the pins 289 and 287, such pins engaging the upper and lower edges of the spear head and being gradually spread apart thereby or, in other 75 words, the pin 289 is forced downwardly in the slot 263 carrying the jaw member 265 away from the jaw member 266. When the pin 289 has passed the lower end of the spear head the jaw member 265 is forced 80 outwardly by the compression spring 290 thereby carrying the pin 289 toward the pin 287 and into circumferential alignment with the channel portion 297 of the spear head so that when the arm 243 is again 85 swung back toward the position shown in the drawing the pin 289 engages such bevel portion forcing the head 295 inwardly against the tension of the spring 294 thereby allowing the pin to pass. 90

298 and 299 indicate vertical ways formed in the back of the plate 5. The upper end of the way 299 is provided with an opening 300 for a purpose which will hereinafter appear. The way 298 is dove-tail in form and 95 provided with a vertical casing 301 extending vertically of the front face of the plate 5. 302 and 303 indicate standard plates extending inwardly from the plate 5, the plate 303 being carried by an inward extension 100 304 and the plate 302 by the wall of the casing 301. 305 indicates a slide provided with a dove-tail portion 306 slidably held within the way 298. 307 and 308 indicate vertical grooves formed in the slide 305 and 105 extending from the top to the bottom of the same. 309 indicates a bar piece fitting within the vertical groove 308 and pivotally secured therein at its lower end by a pin 310. The slide piece 305 is provided at one 110 side with an upward extension 311 provided with a vertical slot 312 open at its upper end. The piece 309 is provided at its upper end with a lateral extension 313 terminating in a forwardly extending portion 314 passing through the open end of the open ended slot 312. 315 indicates a piece slidably held in the groove 307 and 316 indicates a notch formed in the lower end of the slide piece, such notch forming a lateral extension of 115 the vertical groove 307. 317 indicates a portion extending forwardly from the lower end of the piece 315 so as to protrude through the notch 316. 318 indicates a tension spring connecting the portion 317 with 120 a stationary pin 319. 320 indicates a lateral extension to the upper end of the piece 315, such lateral extension terminating in a forward extension 321, such forward extension being provided with an upwardly extending 125 130

notch 322 at its lower end. 323 indicates a saw cut formed in the upper end of the slide piece 305 and forming a lateral extension to the groove 308. 324 indicates a 5 tongue formed on the piece 309 and extending forwardly through the saw cut 323, such tongue being provided with an inclined upper edge 325. 326 indicates a vertical slot formed in the side of the casing 301. 327. 10 indicates a bell crank piece pivotally mounted on the plate 5 to the outside of the casing 301 in such a position that the horizontal arm of the bell crank protrudes through the upper end of the slot 326 into the casing 15 301, the lower end of the vertical portion of the bell crank 327 bearing against the lower end of the slot 326 being held thereagainst by a compression spring 328.

It will thus be seen that as the slide piece 20 305 passes upwardly the inclined portion 325 of the tongue 324 engages the horizontally extending portion of the bell crank 327, which is held rigid from upward movement and thereby forces the pivoted piece 309 25 outwardly from the slide piece at its upper end and thereby carrying the inward extension 314 out of the path of the cord which is being fed on to the top edge of the plate 5.

328* indicates a plate which is secured 30 to the outer face of the slide piece 305 and extends over the outer edge of the vertically movable piece 315 thereby holding such piece in place. 329 indicates a leaf spring which is carried by the plate 328 and bears 35 at its upper end against the laterally extending portion 313 of the pivot piece 309. It will thus be seen that when the tongue 325 has passed in its upward vertical movement the horizontal arm of the bell crank 40 327 that the pivot piece is forced back to its normal position carrying the extension 313 into a position over the cord carried by the upper edge of the plate 5. 330 indicates a projection extending inwardly from the 45 casing 301 into the guideway 298 so as to be vertically in the path of the inward extension 317. As the slide piece passes to its uppermost position the extension 317 engages with the projection 330 thereby forcing the piece 315 downwardly against the 50 action of the spring 318 and carries the inward extension 321 away from the inward extension 314 into the position shown in Fig. 14. 331 indicates a block provided 55 with an inclined upper edge 332, such block being preferably adjustably held in position by a set screw 333 passing through a vertical slot 334 formed in the wall of the casing 301.

60 It will thus be seen that as the slide passes downwardly to its lowermost position the tongue 324 engages with the inclined portion 332 of the block 331 thereby again swinging the pivot piece 309 away from the 65 guide piece 305 against the tension of the

spring 329 so as to again carry the inward extension 314 out of the path of the cord. 335 indicates a cord carrier. 336 indicates an arbor journaled in the opposing plates 302 and 303, the central portion of the arbor 70 being preferably rectangular and extending through a correspondingly formed orifice in the carrier 335. 337 indicates a guide secured to the upper end of the carrier 335 and provided with opposing guides 338 and 339. The base of the guide 337 is cut away at 340. 341 indicate a pair of spring fingers secured to the shank of the carrier 335 and extending upwardly beneath the cut away portion 340. Each of the 80 spring fingers 341 carries a curved portion 342 at its upper end normally bearing against the upper walls of the guides 338 and 339. 343 indicates a spring finger also secured to the shank of the carrier 335. The 85 spring finger 343 extends upwardly beneath the spring fingers 341 and past the end thereof and is provided with a cross bar 342* provided with open eyes 343* and 344* through which the ends of the cord 90 portions are drawn as hereinafter described. 343* indicates a pinion mounted upon one end of the arbor 336. 345 indicates a vertical guideway carried by the plate 303. 346 indicates a rack bar slidably held in the 95 guideway 345 and in engagement with the pinion 343. 347 indicates a bell crank lever mounted upon a standard 348 carried by the base 1. 349 indicates an arm provided with an annular upper end 350 swung 100 upon the shaft 6. 351 indicates a link connecting the depending end of the arm 349 to the lower end of the depending portion of the bell crank 347. 352 indicates a link 105 pivotally connected at its lower end to the horizontal end of the bell crank 347 and provided at its upper end with a curved portion 353 pivotally connected at its extreme end to the lower end of the rack bar 346. 354 indicates a cam secured to the 110 shaft 6 from the inner face of which extend pins 355 and 356.

It will thus be seen that when the operating lever 7 is swung in the direction of arrow that the pin 355 is carried into engagement with the arm 349 thereby drawing the arm in the direction of arrow and tilting the bell crank 347 on its pivot and raising the link 352 and rack 346 in mesh with the pinion 343 thereby swinging the 115 carrier in the direction of arrow (see Fig. 2). When the lever 7 is swung in the opposite direction, of course, the pin 356 engages the arm 349 to perform the reverse operation, that is to say, swing the carrier 120 in the opposite direction of arrow back to its normal position.

I will now describe the mechanism by which the guide piece 305 is raised and lowered in the guide way. The guide piece 130

is provided with a lug extension 305*. 357 indicates a link pivotally connected at one end to the lug extension 305*. 358 indicates an arbor journaled in a lug extension 359 of the plate 5. To one end of the arbor is secured an arm 360, to the inner end of which is pivotally connected the lower end of the link 357 above described. 361 indicates an arm secured to the opposite end 10 of the arbor 358. 362 indicates a cam way formed in the cam 354. 363 indicates a link pivotally connected at one end to the arm 361 and at the opposite end to a link 364, which is pivotally connected at 365 to the base 1 of the machine. The pivot pin connecting the links 363 and 364 together carries a roller 366, which co-acts with the cam groove 362. It will thus be seen that when the cam 354 is turned in the direction 20 of arrow (see Fig. 3) that the cam roller 366 is carried outwardly toward the periphery of the cam and that, therefore, the arm 361 is carried in the direction of arrow carrying the arm 360 downward and thereby drawing the guide piece connected to the arm by the link 357 downward. 367 indicates a pin carried by the guide piece 305. 368 indicates an arm swung upon a pin 369 carried by the casing 301. 370 indicates a 30 slot formed on the wall intervening between the casing and guide 299. 371 indicates a horizontal extension to the arm 368. 372 indicates a tension spring connecting the arm 368 to the opposite wall of the casing 301. It will thus be seen that when the slide piece 305 is carried vertically downward that the pin passes clear of the arm 368 allowing the arm to be swung on the pin 369 to carry the lateral extension 371 there- 40 of through the slot 370 and thereby free the carrier 325 to swing in the direction of arrow as above described. 373 and 374 indicate slots formed in the plate 5 in proximity to the outer edge thereof. 375 and 376 indicate brackets secured to the sides of the plate by set screws 377 extending through the slots 373 and 374. 378 indicates a spring finger secured to the bracket 375. 378* indicates a spring finger secured 50 to the bracket 376 by a rivet 377*. 379 indicates a set screw extending through the bracket and bearing against the outer face of the spring finger so as to adjust the tension of the finger upon the cord. The fingers 378 and 378* may be provided with out-turned lip extensions 380 so as to allow the ready entrance of the cord therebetween.

The above structures serve to guide the cord into the groove in the edge of the plate 5 as each length is drawn off the stock.

Having described the principal parts involved in my invention I will briefly describe the operation of the same.

When the lever 7 is thrown in the direction of arrow the shaft 6 and cam sleeve

8 carried thereby are rotated in a similar direction. During the initial movement of the cam sleeve 8 the roller 35 travels through the concentric portion of the cam groove before it enters the spiral portion. During 70 this movement of the roller the needles 21 and 22 are held stationary. By the above operation the cam way 225 (see Fig. 3) is carried in the direction of arrow thereby carrying the roller 232 into the concentric 75 portion of the cam way and thereby raising the knife 210 into position ready for cutting. During this operation the stud 249 engages the arm 243 swinging it upward and past a vertical position until brought 80 into engagement with the roller 240 thereby depressing the corresponding end of the arm 238* against the pressure of the spring 241 thereby carrying the oppositely extending arm 239 in an upward direction to carry the slide piece 215 circumferentially of the plate 5 and thereby feeding the cord 208 which is gripped by the spring ratchet finger 221 through the perforation 206 into position to be gripped between the jaws 90 265 and 266.

As has been before described when the arm 243 approaches this position the head 295 enters between the pins 289 and 287 spreading them apart and drawing the jaw 265 away from the jaw 266 thereby allowing the fed end of the cord protruding through the head 208 beneath the knife 210 to pass between the jaws 265 and 266. As the pin 289 passes the base of the head 295 such pin is released and the jaw member 265 is forced by the spring 290 against the jaw member 266 to grip the cord therebetween. By the upward movement of the lever 7 in the direction of arrow the cam 354 is rotated carrying the roller 366 outwardly in the cam groove 362 toward the periphery of the cam thereby forcing the link 363 longitudinally outward and swinging the arm 361 in the direction of arrow. The outward swing of the arm 360, which is carried by the arbor 358, serves to carry the arm 360 also carried by the arbor 358 downward drawing upon the link 357 and carrying the guide piece 305 downward.

It will, of course, be understood that this initial downward movement of the slide piece 305 is an idle movement as the cord has not been fed to the machine into engagement therewith. By the same movement 120 also the pin 355 is carried into engagement with the arm 349 swinging the arm 349 in the direction of arrow and drawing upon the link 351 tilting the bell crank 347 on its pivot raising the link 352 and rack 346 in 125 engagement with the pinion 343' thereby swinging the carrier 325 in the direction of arrow in an idle movement.

As soon as the roller 35 enters the spiral portion of the cam groove 9 of the cam 130

sleeve 8 the lever 10 is swung forward and the needles 21 and 22 carried into the grooves 187 and 188 so that the slotted openings of the eyes are immediately above the slots 190 and 191. As the eyes of the needles assume this position the cam 156 has been rotated so that the gravity dog 176 drops into the recess 158 rocking the shaft 175 carrying the gravity dog downward and 5 swinging the arm 178 upward, such movement being assisted by the tension spring 179. By means of the link 198 connected to the arm 178 the block 182 is carried upward carrying the ribbon fingers 195 and 196 10 through the eyes of the needles, the extreme ends of such fingers spreading outwardly after their passage through the eyes into the form shown in Fig. 9. As the arm 243 is swung in the direction of arrow (see Fig. 20 3) the gravity dog 259 passes off the periphery of the cam piece 257 and engages the notch 246. The operating lever is then 25 swung in the opposite direction to arrow. By this movement the disk 244 is rotated in the opposite direction of arrow so that the notch 246 engages the pawl 259 to carry the arm 243 in the opposite direction to arrow. As has been before stated the cord 208 has been gripped between the jaws 265 30 and 266 and therefore, as the arm 243 swings in the reverse direction the cord is drawn through the perforation 206 around the peripheral edge of the plate 5 toward the opposite side of the plate. As the lever 7 assumes its final position and the arm 243 has reached the position shown in Figs. 4 and 5, the roller 232 again engages the eccentric portion 227 of the cam way 225 thereby drawing the pitman 234 downward and 35 swinging the knife 210 downward to sever the fed portion of the cord from the stock, the arm 243 finally carrying the severed portion of the cord into the position shown in Fig. 4. As the arm 243 reaches this position the jaw member 266 is released by means of the finger 272 engaging the inclined portion of the cam plate 276 as has hereinbefore been described thereby releasing the cord. Also by the reverse movement 40 of the lever 7 the carrier 335 is swung back to its normal position or the position shown in the drawing, and the guide piece 305 raised. In order that the inwardly projecting portion 314 should pass the cord carried by the upper edge of the plate 5 as the 45 guide piece 305 assumes its uppermost position the inclined portion 325 of tongue 324 engages the horizontal arm of the bell crank 327 thereby forcing the member 309 outwardly on its pivot against the pressure of the spring 329 thereby allowing the inwardly projecting end 314 to pass the cord. It will, of course, be understood that the cord bridges the open upper end of the open- 50 55 60

ing 300 when it is in position on the upper edge of the plate 5 and that the inwardly projecting portion 321 is drawn downward so as to extend directly beneath the cord, such downward movement being imparted to the piece 315 carrying such inwardly projecting portion by the spring held portion 317 engaging the inward projection 330. As the tongue 324 passes above the horizontal arm 327 the inward projection 314 passes over the cord. 55

Simultaneously with the upward movement of the slide piece 305 the pin 367 carried thereby engages with the arm 368 forcing it into the vertical position shown in the drawing against the tension of the spring 372, the horizontal portion 371 passing over the body of the carrier 335 and beneath the spring fingers 241 thereby holding the carrier accurately in position to receive the cord. As the lever 7 is again swung in the direction of arrow the slide piece 305 is carried downward by means of the cam way 362, co-acting roller 366, link 363 and swingable arms 361 and 360 connected by the link 357 to the slide piece. As the slide piece 90 passes downward the tongue 324 engages the horizontal portion of the arm 327 swinging it downward on its pivot against the compression of the spring 328 thereby allowing such tongue to pass downward without affecting the position of the extension 314. Simultaneously the projection 317 is carried out of engagement with the projection 330 enabling the tension spring 318 to draw the member 315 vertically and carry the inward extension 321 upward to grip the center of the cord against the extension 314. It will thus be seen that as the slide piece 305 passes downward that the center portion of the cord is drawn downward into the guideways 100 105 338 and 339 of the carrier 335.

It may be stated that as the carrier is carried into the position shown in the drawing the cross bar 342* and curved portion 342 bear against the vertical edge of the lateral extension 321. As the cord is drawn into the guide-ways 338 and 339 it is also drawn into the eyes 343* and 344* being drawn longitudinally therethrough until the slide piece assumes its lower or dotted position shown in Fig. 5 drawing the cord into looped form. 110 115

When the lever 7 is swung in the direction of arrow the pin 355 engages the arm 349 pulling on the link 351 raising the horizontal arm of the bell crank 347, link 352 and rack 346 so as to rotate the pinion 343' and swing the carrier 335 in the direction of arrow. The cord ends projecting from the eyes 343* and 344* pass between the 120 125 spread apart ends of the ribbon fingers 195 and 196. The fingers 195 and 196 are then drawn down by means of the pawl 176

passing out of the recess 158 carrying the cord through the eyes of the needles.

What I claim as my invention is.

1. In a mantle sewing machine, the combination with the reciprocating needles thereof, of a pair of spring fingers designed to pass vertically through each of the eyes of the needles and to spread outward at their outer ends when passed through such eye and form receiving notches, means for gripping the cord in proximity to its ends and laying such ends into the receiving notches of the spring fingers and means for automatically drawing the spring fingers downward through the eyes of the needles.

2. In a mantle sewing machine, the combination with the reciprocating needles thereof, of a recessed member, a stationary block supported in the open end of such recess and having grooves in longitudinal alinement with the needles and provided with a slot extending through the block from the base of each groove, a vertically movable block held in the recess, spring fingers carried by the movable block and extending upward through the slots of the stationary block and adapted to spread outward at their upper ends when carried free of the slots, means for gripping the cord ends of a cord portion as it is cut from the stock and laying the ends of such cord portion between the outspread ends of the fingers and means for automatically drawing the block downward to draw the fingers vertically through the eyes of the needles and the slots of the stationary block.

3. In a mantle sewing machine, the combination with the reciprocating needles thereof, of a vertically recessed member, a stationary block fitting the open end of such recess and provided with cross grooves in longitudinal alinement with the needles and having slots extending through the block from the base of such grooves, a guide rod extending between the stationary block and the base of the recess, a movable block slidably held upon the guide rod, a pair of ribbon fingers located at each side of the rod secured at their lower ends in the movable block and extending at their upper ends into the slots of the stationary block and adapted to spread apart at their outer ends when carried upward free of the slots, means for gripping the ends of a cord portion when cut from the stock and means for automatically carrying such gripping means into position to lay the cord ends into the spread apart portions of the fingers, and means for then drawing the fingers downward through the eyes of the needles and slots of the stationary block.

4. In a mantle sewing machine, the combination with the reciprocating needles thereof, of a vertically recessed member, a

stationary block fitting the open end of such recess and provided with cross grooves in longitudinal alinement with the needles and having slots extending through the block from the base of such grooves, a guide rod extending between the stationary block and the base of the recess, a movable block slidably held upon the guide rod, a pair of ribbon fingers located at each side of the rod secured at their lower ends in the movable block and extending at their upper ends into the slots of the stationary block and adapted to spread apart at their outer ends when carried upward free of the slots, means for gripping the ends of a cord portion when cut from the stock and means for automatically carrying such gripping means into position to lay the cord ends into the spread apart portions of the fingers, means for then drawing the fingers downward through the eyes of the needles and slots of the stationary block, and a piece extending from the stationary block adapted to engage the looped portion of the cord as the needles recede.

5. In a mantle sewing machine, the combination with the main shaft of the machine journaled in suitable standards and the reciprocating needles of the machine, of a standard member having a vertical open ended recess in its upper end and a stationary block secured to the upper end of the stationary member and bridging the recess and having grooves formed therein in longitudinal alinement with the needles and having a slot extending downward from the base of each groove through the block, a movable block slidably held within the recess, ribbon fingers secured at their lower ends to the movable block and extending upward through the slots of the stationary block, a rocking shaft journaled in suitable bearings, a disk carried by the main shaft having a peripheral notch therein, a hook dog carried by the rocking shaft and bearing upon the periphery of the disk, an arm secured to the opposite end of the rocking shaft and a link connecting such arm intermediate of its length with the movable block.

6. In a mantle sewing machine, the combination with the reciprocating needles thereof, of a standard member having a recess, a stationary block fitting the open upper end of the recess and having grooves in longitudinal alinement with the needles and slots extending vertically from the base of such grooves through the block, a movable block carried in the lower portion of the recess, means for reciprocating the movable block, a pair of ribbon fingers extending at their upper ends into each slot and secured at their lower ends to the movable block, tension means located within each slot and bearing outward against each pair

of ribbon fingers and means for engaging the ends of a cord portion with the ribbon fingers when passed upward through the eyes of the needles.

- 5 7. In a mantle sewing machine, the combination with the reciprocating needles thereof, of a standard member having an open ended recess, a stationary block bridging the open upper end of the recess having 10 longitudinal grooves in longitudinal alignment with the needles and slots extending vertically downward from the grooves through the block, a movable block held in the lower part of the recess, means for re-

ciprocating the movable block, ribbon fingers secured at their lower ends in the movable block and extending upward in pairs into the slots of the stationary block and adapted to spread outward when their upper ends are carried clear of the slots and eyes 20 of the needles and a bow spring located between the pairs of ribbon fingers to force them against the outer walls of the slots.
